COMBINED SOCKET AND MOUNTING PLATE

Arthur J. Schmitt, Chicago, Ill.

Application January 21, 1938, Serial No. 186,165

1 Claim. (Cl. 173—339)

This invention relates to combined socket and mounting plate more particularly for sockets for radio electronic tubes in which the socket is mounted in an opening on a radio chassis or the like.

The molded one-piece socket has many advantages over the conventional socket of laminated insulating material, but problems have been encountered in attaching the molded socket to the chassis. For many years the standard form of radio socket, which has been conventionally of the laminated type, has been diamond-shape with rivet holes near the points of the diamond, and one of the problems encountered with molded sockets has been the maintaining of a structure of this general shape so that the molded socket may be secured interchangeably with a laminated socket on the radio chassis.

Instead of molding the insulating body in diamond-shape, since there are certain distinct advantages in maintaining the generally cylindrical shape of the molded insulating body, it has been proposed to provide a so-called adapter or mounting plate of sheet metal in association with the molded insulating body, and to which the latter is secured. In my co-pending application Serial Number 152,478, filed July 8, 1937, I have shown such an adapter plate separably secured to the molded body, but such attachment of the body and plate is sometimes objectionable in that it is difficult to make the interengagement of the parts so tight as to be entirely free from slight movement and consequent vibration which may affect the radio reception.

In another co-pending application Serial Number 107,526, filed October 26, 1936, I have disclosed an alternative method of securing the body and plate together in which the plate is molded into the body, this latter method being highly preferable by achieving a tight and vibrationless attachment of the parts and making the body and plate in effect an integral unitary socket. The present application is a continuation in part of the said disclosure of my co-pending application Serial Number 107,526.

The present invention aims to provide such a unitary body with molded-in plate which possesses enhanced rigidity while preserving the advantages of the diamond-shape. A further object is the provision of a mounting plate of this general type affording novel means of mounting on the radio chassis other than by riveting.

The present invention also is inclusive of both product and method.

Other objects and advantages will be readily

apparent from the following description, taken together with the accompanying drawing, in which—

Figure 1 is a considerably enlarged and exaggerated cross-sectional view of a radio socket of the class described associated with the usual chassis or the like;

Figure 2 is a view, substantially actual size, of the socket of Fig. 1, and being partly in section taken on the line 2—2 of Fig. 1;

Figure 3 is a plan view, actual size, of the preferred form of mounting plate before the insulating body is molded thereabout;

Figure 4 is a similar view of a modified form of plate in preliminary form;

Figure 5 is a side elevational view of the plate of Fig. 4 with an insulating body molded therein, and with the plate tongues in intermediate position;

Figure 6 is a view of the structure of Fig. 5 secured to a radio chassis with the plate tongues in final position; and

Figure 7 is a view somewhat similar to Fig. 6 but showing an alternative form of mounting the socket to the chassis.

Referring in detail to the illustrative construction shown in the drawing, the numeral 10 indicates in cross-section a panel of the usual radio chassis or the like, upon which the tube sockets are to be mounted. The panel commonly is provided with a circular opening 11 therein which is just slightly larger than the cylindrical insulating portion 12 of the socket in which the contacts 13 are held to engage through recesses 14 in the body with the prongs of a radio vacuum tube (not shown). The contacts 13 are desirably of flat sheet metal having at their upper ends the legs 13a between which the prong of the radio tube is frictionally engaged when received in the recess 14. Transverse grooves 14a extending laterally from the recess 14 not only permit the legs 13a to be received in the body 12 but also the tail 13b of the contact, which as shown is preferably wider than the cylindrical portion of the recess 14. When the tail 13b has been passed down through the slot 14b in the lower part of the recess 14 the tail may then be bent or distorted to secure the contact against displacement upwardly in the body, as shown in my co-pending application Serial Number 107,526. The shoulders 13c formed at the junction of the legs 13a and the tail 13b engage the shoulder 14c in the recess 14 and prevent downward displacement of the contact from the socket. Apertures 13d in the tail are for the

usual soldered electrical connections. A central passage 12a in the body 12 receives the usual central locating plug on the vacuum tube and may include a keyway for fixing the relative rotative position of the vacuum tube and socket, this being well known to the art and not necessary to be here shown. Commonly the panel 10 is provided with diametrically opposite perforations 15 at the margins of the opening 11.

10 Referring first to Figs. 1, 2 and 3, the cylindrical insulating body 12 is held in the opening 11 by the mounting plate 16 (to which it is secured as later described), which plate, as best seen in Fig. 3, is of diamond-shape having the holes 17, in its opposite corners 18, which are made to register with the holes 15 in the panel 10. As shown in Fig. 2, rivets 19 secure the mounting plate 16 across and just beneath the opening 11 in the panel so that the upper end of the cylindrical body 12 projects upwardly just slightly through this opening, and is therefore readily accessible for insertion therein of the prongs of the vacuum tube.

In accordance with the present invention, it will be seen that the central portion of the plate 16 has a central cut-out 20 therein, and the plate is adapted to be formed in large quantities by a stamping operation from sheet metal, not only to provide this central cut-out 20 with its continuously integral margin, but also to form the portions of the plate margining this cut-out, as next described.

Diametrically opposite each other and desirably aligned with the holes 17 in the plate are the inwardly directed lugs 21 which project into the cut-out 20 but preferably in the plane of the plate 16. On each side of each of the lugs 21 is then formed a notch 22. Extending between the pairs of notches 22 and for the remainder 40 of the inner circumference of the cut-out 20 are the diametrically opposite portions 23 of this margin which are distorted somewhat out of the plane of the plate 16, as in this instance by being depressed, as best shown at 24, Fig. 1. The 45 distorted portions 23, as will be seen, are arcuate substantial portions of the inner circumference of the cut-out 20. The insulating body 12, which may advantageously be of Bakelite, is next initially molded in the cut-out 20, as is well 50 known in the art, and need not be described. It is sufficient to state that when so molded in the cut-out 20, the body 12 as here shown is of sufficient final diameter, as best shown in Fig. 1, so that the entire margins of the cut-out 20 including the lugs 21, notches 22 and depressed 55 portions 23 are embedded in the body 12. Thus,

when the body 12 and the plate 16 are molded together they become in effect an integral unitary socket preserving the advantages of the flat plate 16 which does not interfere with the insertion of the cylindrical body 12 in the opening 11 in the chassis panel, and at the same time enhances the strength and rigidity of the central portion of the plate 16 and particularly the otherwise somewhat weak sides 25 of the plate. In other words, distorting the inner margins 23 transforms the sides 25 into beams having tension and compression components, these components being furthermore embedded within the body 12 and the material of the body 12 so flowing thereabout as to further uniquely and positively interlock the body and plate together against any possibility of vibration of one with respect to the other.

Turning now to Figs. 4 to 7 inclusive, the plate might be of the somewhat modified form 26, the central cut-out and its margin being advantageously the same, but the outwardly projecting tongues 27 being formed in place of the ends 18. In such case the tongues 27 may first be turned up as at 28, Fig. 5, then inserted through the holes 15 in the panel 10, and then clinched over the panel as at 29, Fig. 6, thus securing the combined socket and mounting plate to the panel without the riveting operation indicated in Fig. 2.

As a still further method of mounting, the 30 tongues 27 could be left flat, that is, in the plane of the plate 26 as indicated in Fig. 7 and spot-welded to the panel 10 as at 30.

Such changes may be made as fall within the scope of the following claim without departing from the invention.

Having described my invention, I claim:

A device of the class described embodying a flat sheet metal annular plate having an integral generally circular inner margin, a cylindrical 40 socket body of initially plastic insulating material molded within said annulus with the inner margin of the plate embedded within said molded body, diametrically opposite substantially quarter annulus segmental sides of said inner margin 45 being by performing prior to molding inwardly and axially extended out of the main plane of said plate within the body whereby said margin sides function therein as reinforcing beams having both tension and compression components as 50 well as providing a positive non-rotative interlock with said body, said plate having exterior diametrically opposite mounting extensions aligned transversely substantially ninety degrees to said segmental sides.

ARTHUR J. SCHMITT.

CERTIFICATE OF CORRECTION.

Patent No. 2,205,051.

June 18, 1940.

ARTHUR J. SCHMITT.

It is hereby certified that error appears in the printed specification of the above numbered patent requiring correction as follows: Page 2, second column, line 46, in the claim, for the word "performing" read --pre-forming--; and that the said Letters Patent should be read with this correction therein that the same may conform to the record of the case in the Patent Office.

Signed and sealed this 30th day of July, A. D. 1940.

Henry Van Arsdale,

Acting Commissioner of Patents.
